REINFORCED BUILDING CONSTRUCTION

Hayden Edwards, Columbus, Ohio

Application October 18, 1945, Serial No. 623,126

14 Claims. (Cl. 72—42)

1

The present invention relates to building constructions and more particularly it provides certain novel and useful forms of prefabricated slabs, sheets or plates capable of forming the principal structure of a wall, floor, roof or the like.

The principal objects of the invention are to provide structural and functional improvements in buildings and their erection and at the same time to effect substantial economies.

These objects are accomplished mainly by providing an improved type of building unit in the form of a prefabricated slab or the like having a remarkably high ratio of strength to weight which can be manufactured by rapid and economical rolling, stamping or punching or by the use of permanent molds or other methods involving the use of dies and which is adapted to be set up in accordance with any of a great variety of architectural designs quickly and inexpensively by relatively unskilled labor.

A basic principle of the slab element is the use of a skeleton type of construction produced by forming the slab with numerous cavities, openings, channels and indentations which effect economy of material and reduction of weight. This general principle is not new, since the prior art affords numerous examples of building slabs of skeletonized form, generally made with perforations or surface depressions of various kinds. However, so far as I am aware, no previously proposed slab has combined the use of so little weight of material with the attainment of such high structural strength in a product which can be made by the economical methods of rolling, permanent mold casting, or other use of dies, and none has provided the additional advantages of the present invention which will now be briefly summarized.

The slab, sheet or plate which forms a fundamental element of the present invention, which will hereinafter be called a slab, comprises a foundation member in the form of a one-piece sheet or board skeletonized by surface cavities which become closed, at the site where the slab is to be erected or installed in a building or other structure, by the addition of closure elements which are made and transported separately from the slab. In this way the handling weight of the originally separated elements of the completed slab-in-place is materially reduced so that in many cases an individual workman can easily lift the slab base, even when it is made in large dimensions, and mount it in position, although the weight of the completed slab-in-place might

2

be too great for safe or rapid handling without a helper or mechanical assistance. The open surface cavities form convenient seats for the reception of the grappling hooks and the like of mechanical and hand hoisting instruments whenever it is found necessary or desirable to use such instruments.

In addition to its surface cavities, the slab is provided with internal channels or passageways which serve not only to reduce weight and save material but also to receive and enclose various utility conduits such as pipes, wires, etc. An important feature of the invention resides in the fact that these internal openings, which extend in a number of directions through the slab body in a plane parallel to the flat surfaces of the slab, are so disposed that they can be formed in the slab by molding lugs or protuberances formed on dies or the like and pressed inwardly in directions normal to the flat surfaces of the slab. Thus the use of a sand mold or other type of coring operation is rendered unnecessary, so that the slab can be fabricated in a permanent mold or by extrusion between continuously rotating rollers, or by conventional stamping, punching or even drop forging operations.

The surface openings, when covered as contemplated in the set-up slab, form a multiplicity of inter-communicating closed cells through which atmospheric air may be circulated to aerate the slab or a wall, floor, roof or the like made from a plurality of the slabs. In this way the assembled slabs are kept well ventilated and dry.

In addition to their aerating function, the cells may be used to enclose heating, cooling, lighting, air-purifying or other instrumentalities, in which cases the cell covers are modified so as to be heat-conductive, translucent, or permeable to air so that the benefits of the special instrumentalities contained in the cells may be conveyed to the building interior or even, in some cases, to the exterior.

A further advantage of the surface indentations is that they may be left open at the edges of each slab so that each pair of mating halves of such indentations along the joint between abutting slabs may be closed by a single fill which spans the joint line and thus provides a strong keying bond by which the two slabs are virtually laced together.

It is also an object of the invention to dispose cell cavities in a slab in such arrangement that reinforcing mesh may if desired be incorporated in the slab without protruding into the cavities.

Another object is to arrange all the surface cavities in such a way as to leave solid portions of the slab material substantially aligned so as to act as virtual joists or piers when the slab is used as a floor or wall.

General objects of the invention are to provide a novel slab construction which may be disposed in any conventional vertical, horizontal or pitched position in a building, bridge or other structure, so that great structural strength, 10 lightness, durability and general efficiency will be provided at low cost.

The invention also provides means and arrangements for associating slabs together in securely bonded relation, both as the components of an individual wall, floor, roof section or the like, and also as the adjacent members of two or more such sections.

Incidental objects are concerned with attaining novel lighting, heating, cooling, aerating and ornamental effects resulting from the use of a single basic type of slab skeleton base completed by the addition of optionally selected adjuncts such as cell cavity covers and instrumentalities housed in the cells.

The principles of the invention are capable of being embodied in numerous specific forms, certain preferred examples of which are shown in the accompanying drawings in which

Figure 1 is a front elevational view of a slab constructed in accordance with the principles of the invention, showing the interior surface, with the cell cavities uncovered, in the form in which the slab is produced by the casting or rolling operation;

Fig. 2 is a transverse sectional view of the slab taken along the line 2—2 of Fig. 1, but showing the slab completed, ready for use as a building wall, with the cell cavities covered and with a sheet of insulating material applied to the exterior surface;

Fig. 3 is an edge elevational view of the completed slab;

Fig. 4 is an elevational view, similar to the view of Fig. 1, but showing the exterior surface of the slab;

Fig. 5 is a transverse sectional view of the slab taken along the line 5—5 of Fig. 1, at right angles to the view of Fig. 2, but like Fig. 2 showing the slab completed by addition of cell cavity covers and insulation and differing from Fig. 2 by showing a modified form of fastening means.

Fig. 6 is a vertical sectional view through a portion of a building showing walls in interior elevation and section and showing a floor in section, with utility conduits installed in the slabs;

Fig. 7 is a front elevation of a wall slab, or a top plan view of a floor slab, completed with cell cavity covers;

Fig. 8 is a front elevational view of a slab like that of Fig. 1, modified by inclusion of reinforcing, showing the interior surface of the slab completed by addition of cell cavity covers;

Fig. 9 is a front elevational view of the exterior surface of the reinforced slab shown in Fig. 8;

Fig. 10 is a view of the reinforced slab shown in Figs. 8 and 9, showing the right hand edge of Fig. 9 in elevation;

Fig. 11 is a transverse sectional view of the reinforced slab shown in Figs. 8, 9 and 10, taken along the line 11—11 of Fig. 8;

Fig. 12 is a view similar to that of Fig. 10 but showing an upper or lower edge of Fig. 9;

Fig. 13 is a vertical sectional view taken

through the junction of a wall and floor, showing a preferred manner of bonding slabs thereof;

Fig. 14 is a vertical sectional view taken through a wall and roof, showing preferred modes of bonding slabs in the roof sections and to the wall slabs;

Fig. 15 is a front elevational view of a slab like that of Fig. 1, showing the cell cavities formed on the exterior surface and covered by lenses;

Fig. 16 is a vertical sectional view taken through the walls of a building, near a corner thereof showing, in vertical transverse section and in interior surface front elevation, wall slabs having their outer surface cell cavities covered by lenses and having their inner surfaces lined with sheets having pockets closed by heat-transmitting covers;

Fig. 17 is a front elevational view like that of Fig. 15 but showing the cell cavities provided on the inner or outer surface and covered by plate glass panes;

Fig. 18 is a vertical sectional view like that of Fig. 16 but showing the cell cavities and pockets provided with electric lighting, heating or air purifying means and closed by flat covers;

Fig. 19 is a transverse sectional view, like that of Figs. 5 and 11, showing a modified type of slab in which both surfaces are provided with cell cavities;

Figs. 20 and 21 are plan views of the opposite faces of a pair of floor slabs, or elevational views of the opposite faces of a pair of wall slabs, bonded edgewise together in place in a building or the like;

Fig. 22 is a transverse sectional view, taken along the line 22—22 of Fig. 21, through the joint of Figs. 20 and 21; and

Fig. 23 is a transverse sectional view through a slab showing the openings in one of its surfaces closed by a filler applied in such a way as to leave the internal passageways open.

However, it is to be understood that the particular embodiments shown by these drawings and hereinafter explained are subject to further modification without departing from the broad principles of the invention as stated in the foregoing outline of objects and as defined by the appended claims. It is also to be understood that not all of the features incorporated in these specific embodiments need be used in the particular combinations shown and described in this application for Letters Patent.

Referring now to the drawings, Figures 1 and 4 show respectively the inner and outer surfaces of one form of basic slab unit 1 embodying the principles of the invention. This form, as well as the others shown by the drawings and hereinafter to be explained, is preferably made of any suitable cementitious or analogous building material capable of being poured in a plastic condition and thereafter setting to rigid condition, by hydration or otherwise, such as Portland cement concrete, burnt clay or terra cotta, fused silica, or the asbestos fiber and cement material now widely used in the building industry and sold under various trade names. However, the form of the slab is such that it is well adapted to be made also of metal, as by die-casting, or by stamping or drop-forging metal sheet or plate stock.

The slab is so shaped that one of its surfaces, hereinafter designated the inner surface 2, is provided with a plurality of substantially hemispherical cell cavities 3 arranged in lines in such a way that the cavities of adjacent lines are

staggered relatively to each other, as is clearly shown in Fig. 1. Each cavity penetrates the slab some five-sixths more or less of the slab thickness, so that the opposite face 4 of the slab is not broken by the cavity. However, this opposite face is broken by a relatively small aperture or perforation 5 establishing communication between the face 4 and the central bottommost point of the cavity. The surface 4 is also interrupted by generally rectangular shaped openings 6 which penetrate sufficiently into the slab material to communicate with cylindrical passageways 7 which radiate from each cavity to connect it with each adjacent cavity. In the arrangement shown, each cavity has six such passageways 7, spaced approximately 60° apart around each cavity, so that all the cavities which are aligned in any direction are connected by aligned passageways 7. This feature I regard as important because the alignment of the passageways facilitates fishing utility conduits and the like through them.

In order to receive lids or closures as will hereinafter be explained, each cavity is surrounded by a widened rim depression forming a shoulder 8 set slightly below the plane of the inner wall 2 of the slab.

The passageways 7 lie all in the same general plane, which is best located parallel to and slightly outwardly from the median plane of the slab.

An important feature of the invention resides in the capacity of the slab to be cast or rolled by fixed, solid molding or roll surfaces, or to be punched, pressed or stamped from plain sheet or plate stock. To this end I make all the cavities, passageways and openings in such form and relationship that all portions of all of them are directly open to one or another of the surfaces 2 and 4 of the slab by straight lines normal to such surfaces. This will be evident from Fig. 2, where it will be appreciated that a single specially shaped molding protuberance or die projection may be used to form each cavity 3 and those portions of its six passageways 7 which are located between each dotted line 9 and the cavity, while another, differently shaped protuberance or projection on a cooperating molding surface or die forms the opening 6 and that portion of the adjacent passageway 7 which lies between the dotted lines 9. Of course suitable projections on one or another of the two molding or die surfaces will be provided to form the perforations 5.

The presently preferred material for the slab is one of the cementitious or plastic type, and the drawings illustrate the slab in the relatively thick form in which such material is best cast, molded or rolled. However, it is to be understood that cooperating dies, configured in the same way as the molding or rolling surfaces, may be set up in a drop forging, punching or stamping press and operated on plain metal sheets or plates of any appropriate gauge to produce a metallic slab of the same general surface and internal contours as the cementitious or plastic slab. The metallic slab can, however, be made somewhat thinner, and it will be found convenient in many cases to make it longer and/or wider because the metal product can be handled with less danger of breakage, cracking or distortion.

It is thus apparent that the particular arrangement hereinabove described and shown in Figs. 1 and 2 combines various functional surface de-

pressions and internal passageways in a slab in such a way that the slab need not be expensively molded or cored out but can be cast by the use of a permanent form or can be extruded between rotating rollers, or can be die-stamped, die-cast or drop forged. For this reason, coupled with the inexpensive material which may be used, the slab is extremely economical to make.

The slab is also unusually light, since the ratio of its voids to its solid material is very high. Notwithstanding this lightness, the slab is structurally strong because of the staggered arrangement of the lines of cavities which leaves a substantially straight or only slightly sinuous line of solid slab material running in one direction between adjacent rows of cavities. Two such lines are seen in Fig. 1, one on each side of the vertical central line of cavities. These lines act in vertical compression as virtual piers or studding when the slab is used as a wall, and when such lines are disposed lengthwise between supports, when a slab is disposed horizontally, they act as virtual joists.

The structure thus far described is made in one integral piece and is of course very light because it is skeletonized by the openings, cavities and passageways. It can be made light enough, even when made in slabs of appreciable length and width, for one workman to carry and set a slab without assistance. The surface openings are intended to be covered after the slab is installed in a building or other structure, and this covering may be accomplished in two principal ways which will now be described.

The surface 2, which is generally and preferably employed as the interior face of a building wall, originally presents the series of cavities 3. These are covered by discs 10 which more or less accurately fit against the shoulders 8 and may be held in place in any convenient way, as by the cement or other plastic keys indicated at 11. Each cover disc 10 may be made in the form of a fairly thin circular plate cast, stamped or otherwise formed from the same material as the slab itself or from any other suitable material. A slab completed by the addition of cover plates 10 presents a surface 2 which is continuous, unbroken and substantially smooth. If this surface be arranged as the interior of a wall or as a ceiling it may be faced by plaster, wall board or any other conventional interior sheathing, or the slab and its covers 10 may be made with such accuracy as to present a smooth, even, finished surface, as is well shown in Fig. 7, which requires no plastering or other preparation prior to receiving a decorative finish of paper, paint or the like.

The surface 4 is broken by the openings 6 and the small perforations 5. It is generally desirable to affix sheet insulation, shown at 12 in the drawings, to this surface when used as the exterior of a wall. One way of accomplishing this affixation is by inserting plugs 13 of any nailable material, such as wood, plastic or the like, into certain of the openings 6 and then nailing the sheets 12 to these plugs. Thus the exterior surface of the wall is finished, and of course any conventional surfacing trim may be applied, such as stucco, board sheathing or the like.

The slabs may be made in any convenient length and width, but it is best to make their dimensions in multiples of each other and in multiples of the distance from center to center of the cell cavities. It will also be found desirable in most cases to provide two intersecting edges of each slab with a tongue 14 and the other

two edges with a complementary groove 15 so that adjacent slabs can be interfitted together. Of course all the edges might be grooved and the mating grooves of adjacent slabs be filled with some independent keying material.

A plurality of slabs, as cast, rolled or pressed in the skeletonized form which has been described, are set edge to edge in vertical position to form a wall, with the tongues 14 interfitted into the grooves 15 and with the cell cavities 3 open to the interior surface. These cavities are then closed by the cover plates 16, and the exterior surface of the wall is sheathed by installing plugs 13 at selected intervals and nailing or otherwise securing sheets of insulation 12 to these plugs. Optionally, the insulation may be mounted by means of bolts 16 passing through the perforations 5 and engaged with nuts and washers 17 in the cells, as shown in Fig. 5. These bolts may be conveniently extended beyond the insulating material surface as shown in Fig. 5 as a means for tying exterior facing.

Fig. 6 illustrates a corner of a building in which two intersecting walls are formed of completed slabs and in which a floor is similarly formed and tied into the walls. In this figure the bolts 16 are used to mount sheets of insulation, and furring 18 is interposed between the insulation and any conventional type of exterior sheathing 19.

Fig. 6 also shows a convenient mode of supporting a floor, generally designated 20, on a wall, generally designated 21. In this arrangement the wall is laid up to desired height, so as to terminate in a single course of slabs providing a continuous horizontal top edge surface. This surface provides a bearing for the margins of a floor slab which is laid on it, and the upper edge of this floor slab in turn provides a footing for the course of slabs which are then laid up to continue the wall. In this way the floor is securely keyed into the wall.

It will be understood, with reference to Figs. 6 and 1, that the floor slabs are laid in such a way that the aligned cell cavities shown extending in vertical lines in Fig. 1 extend across the span between the walls which serve as bearings for these slabs. Thus the solid slab material, lying in almost straight lines between the aligned cell cavities, serves as virtual joists from bearing to bearing and renders unnecessary the use of actual joists, beams or any other supporting means.

Fig. 6 also shows certain of the passageways 7 employed to house utility conduits 22 which can easily be fished through those of the passageways 7 which are continuously aligned in any direction. Thus, as shown in Fig. 6, the conduits may extend in a vertical direction through the walls, in a horizontal direction through the floor, or in any inclined or diagonal direction through the floor or walls. These conduits may be led into or out of the wall through the surface 2, from any of the cavities 3, by omitting the cover disc 10 from such cavity or by providing a hole in it, and they may be led through the surface 4 from any of the openings 6 or perforations 5.

When used as a floor I prefer to dispose the slabs with their cavity surface 2 uppermost. The cavities may if desired be subsequently closed by covers 10 to provide a foundation for any conventional type of flooring 23.

The surface 4 of the floor slab forms the foundation for a ceiling which may be built up in some such way as is indicated in Fig. 6, where a sheet of insulation 24 is hung from the slab by

means of bolts 25 passing through some of the perforations 5. This insulation may be covered by any suitable ceiling surface material, as indicated at 26, being fastened in place by the same bolts.

If desired or thought necessary, the quarter-spherical or half cavities which open to the edge of the top course of slabs in the wall 21 (one of such cavities being shown at the top center of Fig. 1) may be filled with cement to assist in bonding the wall and floor margins together. Such bonding is employed in Fig. 14 at 27 to secure together the two sections 28 of a pitched roof and also at 29 to secure the lower edge of a roof section to a cornice 30 which caps a wall 21.

In the alternative, a floor 20 may be bonded to a wall 21 by a key 31 filling one of the wall cavities and the adjacent floor half cavity as shown in Fig. 13.

Figs. 20 and 21 show the joint by which a pair of adjacent slabs are bonded together in a wall, floor or roof section. It will be observed that the half-openings 6, open to the edges of the two slabs, become aligned with each other and provide keyways for receiving fills 32 of bonding material, preferably a cement introduced in plastic condition and subsequently setting, thus providing a laced bond for the joint. In order to keep such plastic bonding material from filling the passageways 7 I form a shoulder 33 along the plane at which each opening 6 meets the adjacent passageway 7 along the long dimensions of the openings. Plates 34 of some suitable thin sheet material, which may be as inexpensive as cardboard, are laid on these shoulders to support the cement until it hardens and thus prevent it from entering and obstructing the passageways 7. If desired or thought necessary, the joint can be strengthened by tying adjacent slabs together by bolts or the like passed through the mating passageways 7 which are intersected by the joint line.

Figs. 8-12 show a modification of the slab structure in which reinforcing is incorporated. This reinforcing, designated 35, may take the form of a series of wires or rods or coarse woven wire mesh so dimensioned that all the wires will lie in the solid portions of the slab and none of it will protrude into any of the cavities, passageways or openings. Such a reinforced slab is fabricated, installed and completed in the same way as has been described in connection with the unreinforced slab.

Fig. 19 shows a further modified type of slab in which both surfaces are provided with open cavities 36. All the cavities are staggered with relation to each other so that maximum strength of the skeleton structure is preserved. Each cavity may be closed after the slab is installed by addition of a closure disc or plate 10. Slabs made in this form are primarily useful as the walls of structures which do not require insulation or other type of outer sheathing, and they are useful also in horizontal position as girders or as the floors of short span bridges, culverts and the like, or in horizontal or pitched position as a roof, in all of which uses some plastic surfacing material can be inserted or poured into the cavities after the structure is mounted in place. In this way the weight of the slab or the like is kept low for ease in handling, transportation and installation.

Figs. 15 and 16 show a modification in which slabs used to form walls are positioned with their cavity surfaces 2 on the outside and in which

the cavities are closed by double convex lenses 37 each held in place against the shoulder 8 by some such means as a bezel. These lenses concentrate solar rays at focal points in the cavities where the heat is absorbed by an appropriate fluid in one terminal portion 38 of a coil 39 which extends through the perforation 5 at the base of the cavity and terminates in a portion 40 on or in the interior surface of the wall. It is convenient to mount the terminal portion 40 of each coil in a pocket 41 formed in interior wall sheathing and covered by a perforated closure plate 42. Heat generated in the coil is thus transmitted through the wall and into the interior of the building by passing through the perforations in the plates 40.

The coils may be connected in series with each other and with a pump and reservoir in which sun heat can be stored for recirculation after sundown.

Figs. 17 and 18 illustrate a further modification in which transparent or translucent panes 43 are substituted for the lenses 37 and for the perforated closure plates 42. Such a wall is intended to be impermeable by heat and air and hence may include a sheet of insulation interposed between the wall slab and its outer sheathing 44, closing the perforations 5. Electric light bulbs 45 and 46 may be positioned in the sheathing pockets 41 and in the cavities 3 to give various illuminating effects to both the inside and outside surfaces of the wall. Such a wall, and of course also a ceiling similarly constructed, may be used in the form of an isolated panel to give novel effect to a store front, theater lobby or the like, or the interior surface arrangement may be employed with a plain exterior, made as in Fig. 6, to provide ceiling or wall lighting.

For the illuminating bulbs of Fig. 18 there may be substituted ultra-violet ray bulbs or their equivalent for sterilizing the air in the cavities, and this air may be circulated, by way of the passageways 7 which connect the cavities, into the building interior through perforated closure plates like those shown at 40 in Fig. 16, or through some other type of register. If the panes 43 which cover the sterilizing lamps are permeable to the rays from the lamps, the air in the room will of course be directly sterilized. Such an installation is recommended for use in the operating rooms of hospitals, in kitchens or other places where food is prepared, in pharmaceutical factories, or any other place where a highly sterile atmosphere is desirable.

In all forms of the invention, the slabs which are associated in edge to edge relation provide continuous communicating passageways through them. I have explained that any set of such passageways which are aligned in any direction may be selected to house wiring, piping or the like. These passageways and the remaining ones may be used also to conduct heated or cooled air through the walls from some point or level selected as an inlet to some other point or level serving as an outlet. It will readily be appreciated that walls, ceilings or floors may in this way have their temperature modified and controlled in any desired way. The warmed or cooled air may be recirculated from the passageways to a heating or refrigerating means and back again to the passageways, or it may be exhausted into the building interior or to the outside, in any way desired. It is recognized also that the cell cavities may have mounted in them individual heat radiators, such as those of the

electric filament type, which will warm the slabs and the air contained in them, and that this air may be kept out of the building interior by the use of imperforate closure discs 10, or it may be discharged into the building interior by the use of perforated discs 42. Obviously, individual cooling coil units may be substituted for the heating elements. A desirable arrangement would include the use of both heating and cooling units disposed in different selected cells for operation at different seasons of the year.

It is thought to be clear from the foregoing description and the drawings that the slab provided by the invention may be embodied in the form of a single standard type of skeletonized body to which any of the variety of cell cavity covering elements 10, 37, 42, 43, or others may be selectively applied. While I prefer to make the cell cavities substantially hemi-spherical as

shown in the drawings because the round shape of these openings provides the greatest strength in resistance to compressive loads, the cavities might be made cylindrical, conical, pyramidal or prismatic in shape, since all of these forms are adapted to be impressed in the basic material of the body by die protuberances in casting, rolling, forging, stamping and like processes.

In the appended claims, which point out the broadly novel principles of the invention, the term "building walls and the like" is intended to include not only vertical walls properly so called, whether bearing, non-bearing or "back-up," but also such elements as floors, roofs, ceilings and the like, and the utility of the invention is not limited to buildings per se but is recognized as being applicable to such analogous structures as bridges, decking, bulkheads, etc. The invention is broadly capable of being embodied in numerous forms other than those specifically illustrated and described in the foregoing specification and the drawings and all such modifications are intended to be covered by the broader of the appended claims.

I claim:

1. A building slab comprising a skeletonized body having each of two opposed outer surfaces provided with a set of indentations having their inner portions staggered with relation to the inner portions of the indentations of the other set and intersecting said inner portions, the interior of said slab being provided with passageways formed by said intersecting portions and extending laterally through the body and through the end walls thereof in a plane parallel to the indented surfaces.

2. A building slab comprising a skeletonized body having each of two opposed outer surfaces provided with a set of indentations having their inner portions staggered with relation to the inner portions of the indentations of the other set and intersecting said inner portions, the interior of said slab being provided with passageways formed by said intersecting portions and extending laterally through the body and through the end walls thereof in a plane parallel to the indented surfaces, in combination with closures for covering said indentations.

3. A building slab comprising a skeletonized body having each of two opposed outer surfaces provided with a set of indentations having their inner portions staggered with relation to the inner portions of the indentations of the other set and intersecting said inner portions, all points on the bottom of each indentation of each set lying directly beneath points within said in-

dentation in the plane of one of said surfaces, whereby none of said bottoms is directly covered by any of the material of the body between said bottom and one of said surfaces, the inner portions of the indentations of each set intersecting the inner portions of the indentations of the other set, and the interior of the slab being provided with passageways formed by said intersecting portions and extending laterally through the body and through the end walls thereof in a plane parallel to the indented surfaces, whereby all of the indentations can be formed by die projections pressed vertically to the planes of said surfaces.

4. The slab claimed in claim 2, in which the closures for said indentations are in the planes of said respective surfaces, leaving said passageways unobstructed.

5. The slab claimed in claim 2, in which the closures are individual and separate for covering each of the indentations and cover them in the planes of said surfaces, leaving said passageways unobstructed.

6. The slab claimed in claim 1, in which certain of the indentations formed in one of said surfaces have spaced parallel side walls intersecting the edges of the slab, adjacent pairs of said indentations being open to an edge of the slab in angularly diverging relation, whereby two similar slabs may be laid edge to edge in staggered relation with an indentation of one pair formed in one slab aligned with the corresponding other indentation of a pair formed in the other slab so that the aligned indentations combine to provide a plurality of openings crossing the line of joint between the two slabs at alternately different oblique angles and are adapted to receive and hold keying material to bond the two slabs together and by their different angularity to the line of joint resist separating forces normal to said line.

7. The slab claimed in claim 1, in which certain of the indentations formed in one of said surfaces have spaced parallel side walls intersecting the edges of the slab, adjacent pairs of said indentations being open to an edge of the slab in angularly diverging relation, whereby two similar slabs may be laid edge to edge in staggered relation with an indentation of one pair formed in one slab aligned with the corresponding other indentation of a pair formed in the other slab so that the aligned indentations combine to provide a plurality of openings crossing the line of joint between the two slabs at alternately different oblique angles, in combination with closure plates disposed in the aligned indentations bonding the two slabs together and by their different angularity to the line of joint resisting separating forces normal to said line.

8. A building slab comprising a body having separated substantially hemi-spherical cavities formed in one surface in a plurality of parallel lines with the cavities of laterally adjacent lines staggered with relation to each other and having its opposite surface provided with rectangular indentations arranged in groups extending in directions radiating from the axis of each of the cavities which is normal to the plane of the first named surface, said indentations intersecting said cavities and the intersections forming passageways extending laterally through the body and radially relatively to the cavities and establishing communication between adjacent cavities.

9. The slab claimed in claim 8, in which the

cavities and indentations are closed by separate individual covers disposed between the bottoms of the cavities and indentations respectively and the adjacent surfaces of the body, leaving the passageways open inside the body.

10. A building slab comprising a body having separated substantially hemi-spherical cavities formed in one surface and having its opposite surface provided with rectangular indentations arranged in groups extending in directions radiating from the axis of each of the cavities which is normal to the plane of the first named surface, each of said indentations extending into and intersecting a pair of adjacent cavities and the intersections constituting passageways wholly within the body establishing communication between adjacent cavities.

11. The slab claimed in claim 10, in which adjacent pairs of the passageways are aligned so that utility conduits can be projected through the interior of the body.

12. The slab claimed in claim 10, in which six indentations radiate from each cavity and opposite pairs of passageways of the same group are aligned so that utility conduits can be projected through the interior of the body in any of three different straight line directions.

13. A building slab comprising a cementitious body having a plurality of spaced separated cavities formed in one surface and arranged in parallel lines with the cavities of adjacent lines staggered relatively to each other, in combination with elongated metallic reinforcing elements embedded in the body in straight lines between adjacent cavities.

14. A building slab comprising a cementitious body having a plurality of spaced separated substantial hemi-spherical cavities formed in one surface and arranged in parallel lines with the cavities of adjacent lines staggered relatively to each other, in combination with elongated metallic reinforcing elements embedded in the body in straight lines between adjacent cavities.

HAYDEN EDWARDS.
